UNITED STATES PATENT OFFICE

JOHN S. BEALL, OF PORTLAND, OREGON

FOOD PRESERVING CABINET

Application filed July 26, 1930. Serial No. 471,057.

My invention pertains to food containing and preserving cabinets making use of the evaporation principle of cooling and in that respect it presents no substantial novelty over constructions heretofore known and used for many years.

The objects of my invention are to produce a cabinet of the character indicated that can be readily knocked down and packaged or packed into a relatively small and compact parcel for shipment and handling, and having reached its destination can be assembled by an unskilled person without necessitating any tools whatever and that will result in a construction after assembly that is as rigid and substantial as it would be were it firmly bolted or welded together.

The objects above enumerated are of great utility for the reason that cabinets of this character are largely used in country lodges and rural districts where neither artificial ice nor electric power is available and are commonly purchased by the customer and transported, to the place of use, in a private automobile where a small package is of no substantial disadvantage and where a fully assembled cooler of the type could not be handled at all.

The invention resides in the structural construction making possible the accomplishment of the above enumerated objects at a manufacturing cost believed lower than heretofore possible.

The following drawings accompany and form a part of this specification and with the reference numerals thereon constitute an amplification of the detailed description in the specification.

Fig. I is a front elevation of my new cabinet partly sectioned to illustrate its appearance after assembly;

Fig. II is a top view of Fig. I partly sectioned to show construction details;

Fig. III is a fragmentary view of the bottom of Fig. I to show the method of attaching the legs;

Fig. IV is a view showing the legs, 1, nested for package;

Fig. V is a view illustrating how the entire structure may be knocked down and nested

into a convenient sized package for transportation or storage;

Fig. VI is a section taken at lines VI—VI of Fig. I.

It will be understood that this structure is made from sheet metal as to its frame portion and that all parts wherever possible are joined by autogenous welding so that the joints are smooth and have no rivet or bolt projection to prevent smooth nesting.

Commencing at the bottom of the structure to describe it we find four legs of identical construction indicated by the numeral 1, a bottom pan indicated by numeral 2 having sides, 2a, that are approximately at right angles to the bottom thereof, and made of such dimensions that the superimposed members constituting the balance of the structure will fit smoothly and snugly into it with a vermin-proof joint. Two end members, 3, that are identical in construction, are made of a steel frame having comparatively narrow edges within which is set on the inside portion a substantial wire fabric, 4, upon which is imposed a cloth fabric, 5, such as burlap, the purpose of which is hereinafter disclosed.

A back member, or back side, 6, of identical construction with the end members, 3, and having a length adapted to make the required fit within the bottom pan, 2, is provided in addition to the construction described for the end members, with an angle at each end thereof arranged to stand vertically and designated by the numeral 6a, which provides a locking means for the end members, 3, in conjunction with a similar angle designated by the numeral 7a on the front member, 7. The front member, 7, is provided with a door, 7b.

An upper pan, 8, is provided with a turned over hook, 8a, that locks over the upper end of the end members, 3, and securely holds the said end members from bulging outwardly, the bottom of said end members, 3, being held by 2a at the bottom and by 6a and 7a at the sides, and are therefore held securely at all edges.

The upper pan, 8, is made slightly narrower than the width of the end members, 3, and the ends thereof are hooked at 8a to

lock over the end members, 3, and this hook has a suitable number of slots, in this case three, designated by numeral 8b, for the wicks, 9.

5 A cover plate, 10, is made of the proper size to fit over the entire assembly and provide a dust and vermin proof cover for the top of the structure. Wicks as shown at 9b rest on the bottom of the pan, 8, which will 10 be filled with water and serve by well known capillary attraction means to convey the contained water in sufficient quantities to the back and sides and their fabric covering of the wire mesh and keep them supplied with 15 sufficient moisture to accomplish the function of the cabinet.

Any surplus moisture being caught and retained by the bottom pan, 2, will tend to neatness and will keep the floor upon which 20 it sets dry.

Shelves, 11, are arranged on the inside of the cabinet and supported by the hangers, 12, which will be sufficient in number and so arranged that a plurality of shelves of 25 different spacing may be accomplished, the shelves being readily inserted before placing the upper pan 8 in position.

In Fig. V, I have shown the knocked down arrangement of the device and how each piece 30 fits inside of the bottom pan until all except the legs have been placed in secure position and making one package that is compact and of dimensions easily handled. Another thing will be observed, that the fabric covered 35 screen members are so packed that there is no possibility of the fabric becoming torn, defaced, or soiled in handling, thus greatly enhancing the salability of the cabinet.

The legs, 1, are easily nested together and 40 make a small package that is not objectionable to handle and are attached to the bottom of the lower pan, 2, by sliding the tongue, 1a, under the clip, 2b, when it is desired to 45 assemble the cabinet. Clips, 2b, will be welded in proper position at each corner of the bottom pan, 2.

Thus it will be seen that I have constructed a cabinet that will lock together without tools and form an exceptionally rigid, light and 50 strong piece of equipment, any part of which may be renewed should occasion present itself, and which may be packed and shipped to the greatest advantage.

Having thus completely disclosed my new 55 cabinet, what I claim as new and desire to secure by Letters Patent, is—

1. In a cooling cabinet, a bottom pan member, vertical end and side members of the character described adapted to lock together 60 and fit within said bottom pan member, a water containing upper pan member having locking hooks on the ends thereof and a cover member having four locking edges, said hooks and said locking edges embracing the 65 upper edges of said vertical members where-

by all of the tops of the several vertical members are securely held in position.

2. In a cooling cabinet of the character described, a bottom pan member of the character described, side members, end members 70 and an upper pan member of such dimension that they will smoothly fit in the bottom pan member, and a cover member of substantially the same plan dimensions as the bottom pan member adapted to cover the said 75 bottom pan member and its contained elements in a shallow box like package.
